UNITED STATES PATENT OFFICE.

CONRAD JOBST, OF TOLEDO, OHIO, ASSIGNOR, BY MESNE ASSIGNMENTS, TO THE TOLEDO AUTOMATIC BRUSH MACHINE COMPANY, OF TOLEDO, OHIO, A CORPORATION OF OHIO.

BRUSH MACHINE.

Application filed January 7, 1922. Serial No. 527,590.

The invention relates to brush machines of that type in which a number of the operations for the forming of the complete brush are automatically performed in a single machine. 5 Such operations may include the feeding of the bristle stock, the picking of the tufts from the stock, the feeding of wire and the forming of staples therefrom for securing the tufts, the boring of the brush back and the 10 setting of the tufts therein, this including the engagement of the staple with the tuft, the forcing of the same through a nozzle, and the registration of the nozzle with the bored brush back. The machine may also include a pair 15 of holders for the brush backs which are simultaneously and correspondingly adjusted, the one in registration with the boring mechanism and the other with the tuft-setting mechanism, the arrangement being such that 20 in each cycle of operation, one brush back is completely bored and the previously bored back has the tufts set therein.

Among the objects of the invention are: first, to simplify the construction; second, to 25 secure a high degree of accuracy in the performance of the work; third, to attain high speed in production; fourth, flexibility or capability of adjustment by which a large variety of work can be produced on the same 30 machine; fifth, ease in adjustment and repairs. These objects are attained; first, by forming the machine of a plurality of units, each of which is complete in itself and can be separately assembled and easily attached or 35 detached from the main machine; second, by employing as a driving and timing mechanism a simple harmonic movement, largely eliminating cams and associated parts, which are the cause of trouble in most machines; 40 third, by instantaneous and positive control in the stopping of the machine at the completion of its cycle, which avoids destroying or injuring the work just completed; fourth, by utilizing the portions of the harmonic cycle 45 of lowest velocity for impact operations, such as the forming of the staple, picking of the tuft and the depositing of the same in registration with the setting mechanism, while the high speed portions of the cycle are 50 utilized in transporting the parts from one position to another, thereby attaining high speed in production; fifth, by various features of construction as will be hereinafter set forth.

The present application forms a continuation in part of any previously filed application.

Figure 26 is an end elevation of the same.

Figure 27 is a perspective view of the staple forming mechanism with parts broken away.

The several units which together form my improved machine are: First, the bristle-feeding mechanism; second, the tuft picking and delivering mechanism; third, the tuft setting mechanism; fourth, the work-holding 105

- and registering mechanism including a plurality of work holders which are synchronously and correspondingly operated to register the brush backs with the boring mechanism, tuft setting mechanism and with any other mechanism for performing operations thereon. These units are driven and timed from a common mechanism, but they are not so inter-related as to be dependent for the performance of their several functions upon any other of the units. Also, as has been previously stated, the use of cams is largely avoided and a simple harmonic movement is substituted therefor.
- 15 In general construction, 1 is a frame preferably in the form of a pedestal, on the upper portion of which is mounted the shaft 2 which is driven by the pulley 3 from a suitable source of power such as the electric motor 4 and belt 20 5. Each revolution of this shaft completes a cycle of picking and setting a tuft, while the greater cycle for forming a brush is variable and is controlled by the starting and stopping of the mechanism. The shaft 2 is 25 formed with a pair of cranks or eccentrics, which are of unequal throw and are also angularly displaced in relation to each other. As shown, these cranks are formed by a disk which is at the end of the shaft 2 having the 30 crank pin 7 secured thereto with an angular extension 8, which carries a second crank pin 9 of lesser throw. The angular displacement is formed by turning the shank 10 of the pin 7 to carry the pin 9 the required number of 35 degrees, preferably $12\frac{1}{2}$ °, in advance of the pin 7, and the parts are fixed in this relation by suitable means such as the spline 11 on the shank 10 of the pin. Centrally arranged upon the shaft 2 is an intermittent step-down 40 transmission for driving the synchronously and correspondingly operated work holders. This preferably consists of a helical gear having a portion 13 of its circumference of the required lead and parallel overlapping portions 14 and 15 of zero lead. This gear intermeshes with a pin gear 16 having involute teeth which engage with the helix, being held stationary while traversing the portions 14 and 15 thereof and being driven rotatively in 45 50 traversing the portion 13. The gear 16 is mounted upon a shaft 17 which extends obliquely downward and is connected by the worm 18 and worm wheel 19 to a transversely extending shaft 20. Upon the shaft 20 is 55 mounted a cam wheel carrying a pair of cams 22 and 23, the function of which will be hereinafter explained. The shaft 2 has also mounted thereon a cam 24 which directly actuates the drilling mechanism.
- 60 All of the various units of the machine are actuated and timed by this simple drive mechanism just described, and the arrangement is such that the mechanisms driven by the cranks 7 and 9 have all impact operations performed 65 in the portions of the cycle adjacent to the
- dead centers thereof, while operations of translation are performed in the portion of the cycle having higher velocity.
- Bristle feeding unit.*
- 25 is an upwardly extending portion of the frame, which is provided with two laterally extending studs 26 and 27. Upon these studs is mounted, preferably in inclined position, the bristle holding receptacle, which comprises top and bottom members 28 and 29 and parallel side members 30 and 31. The latter are provided with lugs or bosses 32 which are sleeved upon the studs 26 and 27 and are secured in different positions of adjustment by set-screws 33. The form of the receptacle is preferably flaring from its upper towards its lower end, the side plates 30 and 31 being set for the various lengths of bristles used and the body of bristles being fed downward by a follower 34. The latter is mounted upon a shank 35 which passes through a spring housing 36 and is provided at its upper end with an operating handle 37. The follower is also provided with bifurcated projections 34^a and 34^b respectively embracing the top and bottom members 28 and 29. 38 is a spring sleeved upon the shank, one end abutting against the outer end of the housing and the opposite end against the follower. Thus a yielding pressure is placed upon this follower, which will feed the bristles downward and at any time when it is desired to refill, the follower may be retracted by the handle 37, a latch 39 engaging a notch in the shank serves to hold the follower in its outer position during the loading of the receptacle.
- To provide access to the receptacle, a portion 40 of its top wall is hinged at 41 and is normally held in position by a latch keeper 42 having an operating handle 43. When this latch is released, the member 40 may be turned up, permitting the insertion of the bristles and the filling of the receptacle therewith. At the lower end of the receptacle there is arranged an obliquely inclined member 44, which forms a tapering or wedge-shaped space at the apex of which the bristle picking mechanism is located. This member 44 is reciprocated during the operation of the machine and in its forward movement permits the whole body of bristles to be fed forward and downward, while in its rearward movement the bristles in the wedge-shaped space are pressed downward so as to render the density substantially uniform. Thus the function of the parts thus far described is to feed the body of bristles to the apex of the wedge-shaped space and into operative relation to the tuft picking mechanism, which will now be described.
- Tuft picking and delivering mechanism.*
- Upon the portion 25 of the frame is mounted a vertically extending guide-way 45, in

which are arranged a pair of reciprocating slides 46 and 47. The slide 46 has projecting therefrom a pin 47^a which is engaged by a slotted bearing 48 in a bell crank lever 49. 5 The actuating arm 50 of this bell crank lever extends downward and is connected by a link 51 to the pitman rod 52 actuated by the crank pin 7. Thus in each cycle of the crank shaft 2 a reciprocatory and substantially harmonic movement is imparted to the bell crank lever 49, which in turn actuates the slide 46. The slide 47 is indirectly actuated from the slide 46 and with a lost motion and resiliently yieldable connection. This comprises a laterally extending finger 53 rigidly secured to the slide 47 and extending into a slot in the slide 46. In this slot is the spring 54 having the plunger 55 on which it is sleeved, and said plunger is pressed by the spring against 15 the finger 53. Upward movement of the slide 47 in its guide 45 is limited by an adjustable stop 56 and movement of the slide 47 relative to the slide 46 during the downward movement of the latter is limited by the adjustable stop 57. Thus, when actuated by the lever 49, the slide 46 will first move in a downward direction, while the slide 47 is held stationary against the stop 56, but upon contacting of the stop 57 with the finger 53, both slides 20 will move together to the completion of their downward movement.

The picking of the tuft is accomplished by a pair of cooperating picking needles, carried respectively by the slides 46 and 47, in conjunction with the reciprocating member 44 and other elements, which will be presently described. The all-essential feature in the successful picking of a tuft is to obtain tufts of uniform volume in successive operations 40 and to separate such tufts from the mass and transfer them to the setting mechanism without injury to the bristles. In the rapid operation of the machine the engagement of the picking needles with the bristles forming the tuft must be accomplished in the brief interval between the rising of the needle above the stock and the subsequent descent thereof. If the needles were moving at uniform velocity, this interval would be very short, but by 45 reason of the harmonic movement, the rise of the needle above the stock is during the passage over the dead center. Thus, from twenty to forty degrees of the cycle is occupied by this portion of the movement.

50 Another difficulty in obtaining tufts of uniform density and volume is due to the inertia and friction factors. Therefore, if the bristles are pressed from one direction only into engagement with the needles, there will be a lack of uniformity, but this is largely overcome by pressing from transverse directions. With my improved mechanism the portion of the body of bristles from which the tuft is separated is subjected to pressures 55 in transverse directions in advance of the

separation by the picking needle, which insures a full volume of bristles in each tuft.

In detail, the bottom member 29 of the bristle receptacle is preferably provided with a short horizontal portion 58 adjacent to the apex of the wedge-shaped space, which portion terminates in the vertically extending guide-way 59. Carried by the bifurcated parts 61 and adapted to be brought into registration with the guideway 59 is a guide 60 which through the adjustment of part 44 at 70 75 76 may vary the space between the same and the guide-way 59. The member 44 is also provided with a vertically extending portion 61 which is complementary to the guide-way 60 80 and overlaps the same but is movable relative thereto in the reciprocation of said member. The guide-ways 59, 60 and the extending portion 61 are vertically slotted for the passage of the picking needles 62 and 63 that 85 are respectively carried by the slides 46 and 47. Also, the portion 58 is centrally slotted for the passage therethrough of a presser point 64 which is carried by a reciprocating member 65 arranged beneath the receptacle. 90 The arrangement is such that the forward ward movement of the member 44, previously described, will enlarge the space for the bristles adjacent to the picking needles, so that a forward movement of the presser point 95 64 will carry the bristles into such enlarged space. On the return movement of the member 44 pressure is exerted by the inclined face 66 thereof both downward and rearward upon the bristles and in opposition to the pressure from the point 64 forming in effect a 100 closing in of the space from the sides and top against the bottom 58. This will give the required density to the bristles or, in other words, will completely fill the space with the 105 same so that the descending picking needles will separate a tuft of exactly predetermined dimensions.

The picking needles 62 and 63 are so fashioned as to completely surround the tuft after 110 the picking of the same and during its transfer downward between the guides 59 and 60. To this end the needle 63 is provided with a hook or shoulder 67, which, when the slide 47 is at the upper limit of its movement, is in 115 alignment with the portion 58. The shank portion of this needle extends upward to the slide 47 and is pivotally attached thereto at 68. 69 is an arm or finger extending laterally from the needle above the pivotal point, and 120 70 is a screw carried by the slide 47 forming an adjustable stop for said finger. 71 is a spring pressing against the shank of the needle to yieldably hold the same against the stop 70. On the guide 45 is placed a cam 125 72 with which the finger 69 contacts when the needle is nearing the lower end of its movement, said cam operating to tilt the needle upon its pivot and to laterally withdraw the hook or shoulder 67. The needle 62 is rig- 130

idly attached to the slide 46 and at its lower end is provided with the picking point 73 and with the laterally extending shoulder 74. The point 73 is in alignment with the face of the guide 59, and the whole arrangement is such that the descent of this point, while the needle 63 is stationary, will separate the bristles forming the tuft from the adjacent ones in the wedge-shaped space between the members 44 and 58.

It has been stated that the member 44 is reciprocated to effect the feeding movement and the compacting of the bristles, as previously described. This reciprocation is effected by a connection to the bell crank lever 49, which, as shown, comprises a slotted link 75 engaging a pin 76 projecting from said lever. The opposite end of the link 75 is pivotally attached to a lever 77 and the opposite end of this lever is pivotally attached to the member 44. 78 is a friction bearing for the lever 77 which is under the yielding pressure of a spring 79 sleeved upon the fulerum pivot 80, and the arrangement is such that the lever, after actuation by the link 75 at one end of its stroke, will remain stationary until the lost motion is taken up by said link in its return movement and it is again actuated in the opposite direction. The lower end 30 of the member 44 is bifurcated to embrace the needles 62 and 63 and also a stationary bearing 81 projecting upward from the guide 60. The member 44 is further guided upon a pin 82 which engages slotted bearings in the furcations of said member and this pin is vertically adjustable, preferably by mounting it upon an eccentric 83 rotatively mounted in the bearing 81. The eccentric may be adjusted by a milled head 84, and a set-screw 85 is provided for holding the parts in any position of adjustment.

The presser point 64 carried by the reciprocating member 65 is actuated by a reciprocating slide 86, which is mounted in guide-ways 87 on the portion of the frame 25. The slide 86 in turn is actuated by a slide 88 arranged beneath the same, which latter slide is actuated by a pin 89 coupled to the pivotal connection of the pitman 52 and link 51. Thus the slide 88 will reciprocate the full stroke of the pitman, but the slide 86 is only actuated at the opposite ends of said stroke by a lost-motion connection between the same and the slide 88. This lost-motion connection consists of a finger 90 projecting downward from the slide 86 through a slot in the guide-way therefor, which finger lies in the path of yielding bumpers 91 and 92 on the slide 88. 93 and 94 are springs for the bumpers 91 and 92 which abut against the threaded bushings 95 and 96. Therefore, at each end of the stroke of the pitman and slide 88, movement is transmitted through the bumpers and finger 90 to the slide 86. Upon this slide 86 is a pivot pin 97 forming the connec-

tion between the same and the member 65 by which the movement is transmitted to the presser point 64. It is, however, necessary that the point 64 should be moved upward into engagement with the bristles before the forward movement of the point and also withdrawn from the engagement with the bristles before the return movement thereof. This is accomplished by a rock arm 98 connected to the member 65 and engaging a cam 99 on the slide 88. The cam is so fashioned that the arm 98 will be raised and lowered at the proper times to effect the insertion and withdrawal of the presser pin 64.

Tuft setting unit.

The tuft setting unit comprises a nozzle which is registered with the transfer guide-ways of the tuft picking mechanism to receive the tuft from the needles and is then moved forward into contact with the brush back and in registration with the bore for receiving the tuft. The unit also includes a staple-forming mechanism and an inserter which actuates the formed staple to engage the same with the tuft and then to deliver tuft and staple into the bore of the brush back. Another element of the unit is a shield or deflector which is carried in operative relation to the nozzle and which functions to press a previously set tuft out of the way when a new tuft is to be inserted. Finally the unit is associated with a wire-feeding mechanism which supplies the wire for forming the staples. In structure the unit comprises a housing or guide-way 100 containing four slides 101, 102, 103 and 104. The slide 101 is actuated by a pin 105 extending through a slot in the housing and connected to the pitman 106 which engages the crank pin 9 having the smaller throw. The slide 103 is actuated by the pin 89, previously described, as operating the slide 88. This pin 89 is fixedly secured to the slide 103 and during the assembly of the unit with the other units of the machine may be inserted through the hollow pivot bushing 107 connecting the pitman 52 to the link 51. The pin 89 travels through a slot 108 in the housing and for the full stroke of the large throw crank 7. The slide 102 is yieldably coupled to the slide 101 through the medium of a lug 109 projecting laterally from the slide 102 into a recess 110 in the slide 101. Within this recess is housed a spring 111, one end of which abuts against said lug and the other against the end of the recess said spring surrounding a shank 112. A stop 113 on the housing arrests movement of the slide 102 at the completion of the stroke of the slide 101 and the yielding of the spring 111 permits such arrest.

Between the slides 101 and 102 is arranged the staple-forming mechanism and also the inserter, which latter is actuated by the slide 130

103. The wire for forming the staple is fed vertically upward through a guide-way 114 (see Figure 1) secured to the housing 100 and through a recess between the slides 101 and 102 of substantially the width of the wire. Projecting into this recess from the slide 101 and in rear of the wire is the staple former 115, which is bifurcated to receive the bent staple therebetween. Cooperating with the former 115 is the core or anvil 116 which is at the end of a pin 117 passing through the slide 102 and through the recessed block 102^a attached to said slide. The end of this pin has an oblique face which engages a cam 118 stationary on the housing and a spring 119 presses the pin outward towards the cam. Thus, while the slide 102 is stationary and the slide 101 is moving, the former 115 will travel in relation to the core or anvil 116 and also in relation to the guide 114, first shearing the portion of the wire projecting from said guide and then bending it around the anvil to form the staple. In shearing the wire the cut is oblique so as to form sharpened ends upon the staple for driving into the brush back.

The tuft inserter 120 lies between the slides 101 and 102 and also between the furcations of the former 115. This inserter is actuated from the slide 103 through the medium of a transversely extending blade 121 which passes through a longitudinal slot 122 in the slide 102. During the movement of the inserter 120 the slides 101 and 102 are also moving and in the same direction, but by reason of the greater throw of the crank 7, the inserter will over-take the staple and will then drive it forward into the nozzle 123 and through the latter into the registering hole in the brush back.

The nozzle 123 is provided with the vertical guide slot 124 therein, which is initially in registration with the slot formed by the guides 59 and 60, so that the tuft conveyed downward by the needles will be deposited therein. Centrally through the nozzle is the recess 125, which at its forward end is of the proper size for the passage of the tuft, but which flares towards its rear end in a horizontal plane to receive and bend the bristles. In a central vertical plane there are formed grooved staple guides 126, which receive the staple from between the furcations of the former 115 and guide it in its continued movement to the end of the nozzle. 127 is the shield or deflector which is normally arranged in front of the nozzle 123 and which is mounted upon the forward end of the slide 104. The latter is actuated from the slide 102 through the medium of a pin 128 projecting into a recess 129 in said slide, and a spring-pressed plunger 130 in said recess normally holds the pin at the forward end thereof. This construction permits the slide 104 to move with the slide 102 until near the comple-

tion of the forward movement when a laterally projecting lug 131 on the slide 104 strikes against a stop 132 in the housing and arrests further movement. The slide 102, however, continues to move forward which causes the nozzle 123 to press the shield or deflector 127 laterally out of the way of the tuft and staple and at the same time, by the movement of said deflector, to clear the path of bristles from the previously set tuft. During the transfer of the staple and during the forward movement of the inserter, the core or anvil 116 must be withdrawn from the path and this is accomplished by the forward movement of the slide 102, withdrawing the end of the pin 117 from the cam 118, whereupon the spring 119 withdraws the core.

Wire feed unit.

The wire feed unit consists of a pair of feeding rolls 133 and 134 mounted on the frame below the wire guide 114. These rolls are geared together to operate in unison and are actuated by a pawl 135 carried by a slide 136 located in a guide-way in the frame beneath the housing 100. The slide 136 is yieldably pressed forward by a spring-pressed plunger 137 located in a recess in the frame and which engages a pin 138 projecting laterally from the slide. In the opposite direction the slide is actuated by the slide 103 near the completion of the rearward movement thereof and by means of an upwardly extending finger 139 extending into the path of said slide. An adjustable stop 140 engages a finger 139 and bears against the end of the frame to limit the forward movement of the slide 136 when released by the slide 103. Thus, by adjusting the stop 140 any degree of movement desired may be imparted to the slide 136 and from the latter to the pawl 135, which engages the ratchet wheel 141 connected with the roll 134. The pawl 135 is yieldably pressed into engagement with the ratchet wheel by a spring 142.

Drilling mechanism.

The drilling mechanism for the brush backs is actuated by the cam 24 and consists of a revoluble drill spindle 143 having a drill chuck 144 at its forward end and a pulley 145, which is preferably driven by a plurality of belts 146, thereby insuring continuous operation should one belt break. The spindle 143 is mounted in a bushing 147 within a longitudinally movable plunger 148, which latter is mounted in a bearing 149 on the frame. The bushing 147 abuts at one end against the pulley 145 and at its opposite end against a thrust collar 150, thereby communicating end thrust to the spindle while permitting the independent rotation thereof. The plunger 148 carries a roller 151 which contacts with the cam 24 and this roll is maintained in contact with the cam by a spring 130

152, which is housed in the bearing 149 and bears against a cross pin 153 in the plunger. The cross pin 153 also forms a spline slidably engaging a slotted bearing and thereby holding the plunger from rotation. Adjacent to the chuck 144 is a second bearing 154 for the spindle 143. The whole construction is one in which each cycle of the cam 24 will effect a longitudinal reciprocation of the spindle, 10 while rotary movement is imparted thereto by the belts 146.

Work holders.

As has been stated, my improved machine 15 is of that type in which a plurality of work holders are simultaneously and correspondingly adjusted in relation, respectively, to the drilling mechanism and the tuft setting mechanism or any other mechanism for performing 20 operations upon individual tufts. With such constructions one brush back is drilled while the tufts are set in another back, and the backs are successively transferred from the drilling chuck to the tuft setting chuck. 25 In general construction these holders consist of chucks for correspondingly clamping the brush backs, which chucks are mounted on heads that are simultaneously and correspondingly adjusted in transverse directions 30 to successively register predetermined points in the brush backs with the drill and nozzle. It is also necessary with certain types of brushes to change the angle of the bores so that some or all of the tufts are set obliquely. 35 This is provided for by imparting to the heads a simultaneously correspondingly angular adjustment.

One difficulty which has been experienced with work holders of this type is that in the 40 drilling of the brush backs, where the holes are oblique, there is a tendency for the drill to be deflected from its true position. Consequently, when the drilled back is transferred to the tuft setting chuck, it will not 45 correctly register with the nozzle and imperfect work is performed. One of the important features of my improvement is that provision is made for compensating for this deflection and for changing the amplitude of 50 movement of the tuft setting work holder with respect to that of the boring work holder so as to secure perfect registration. Another important feature of my improvement is the simplification of the mechanism and the 55 elimination of lost motion between the parts, thereby securing a very high degree of accuracy in the performance of the work, as well as decreasing the cost of manufacture and repairs. In detail, the work holders are 60 mounted upon the frame above the shaft 20 and cams 22 and 23 thereon. Centrally between the boring and the tuft setting mechanism is arranged a stationary vertical guide-way 155 containing a pair of reciprocating 65 slides 156 and 157 and upon the lower ends

of these slides are arranged the roller bearings 158 and 159 for respectively engaging the cams 22 and 23. The slide 157 is connected to a yoke 160 which is also guided for vertical reciprocation in the guide-way 155 70 and which carries at its opposite ends a pair of vertically extending rods 161 and 162. These rods pass through the hollow shanks 163 of swivelled heads 164 and 165, said shanks engaging anti-friction bearings 166 which take 75 care of both radial and end thrust. The heads 165 have bifurcated upward extensions or cheek plates 167 which are arranged parallel to each other and equally spaced upon opposite sides of the axes of the rods 162. 168 are 80 frames which are mounted for universal movement between the cheek plates 167, said frames having mounted on their outer ends the brush back holding chucks 169. Near the opposite ends of the frames 168 are pivot 85 pins 170 which extend into guide-ways 171 in the cheek plates and are secured to sliding blocks 172 in said guide-ways. 173 are spring-pressed plungers bearing against the blocks 172 to move the same in their guide-ways to carry the chucks away from the drilling and tuft setting mechanisms. 174 are thrust bars, preferably with a yoke connection 175, which bars are slidably secured in 90 guide-ways in the cheek plates between said 95 plates and the frame 168. The forward ends of the thrust bars 174 are rounded and engage pattern strips 176 which are secured to the rear of the chucks 169 on the opposite sides thereof. The yoke 175 carries a pattern 177, 100 which is arranged in the plane transverse to the planes of the patterns 176 and which bears against a roller thrust bearing 178 arranged in the central plane of the frame 168. The slide 156 is connected with a yoke 185, which 105 embraces the guide-way 155 and has mounted thereon the vertically extending helical racks 186, which engage helical segmental gears 187 mounted on the swivelled shanks 163. With the construction as above described, 110 any vertical movement imparted to the slide 156 will raise or lower the helical racks 186, which in turn will rotate the helical gears 187, thereby imparting to the heads 165 and the mechanism carried thereby an oscillatory 115 movement in the horizontal plane. On the other hand, any vertical movement imparted to the slide 157 will be transmitted through the yoke 160, rods 162, slotted heads 182, to the frames 168, causing an oscillatory movement of the latter in a vertical plane about the pivots 170. By these two movements the chucks 169 may be simultaneously and correspondingly adjusted to any predetermined 120 positions of registration with respect to the 125 drilling and tuft setting mechanisms, while, by reason of the rotation about the pivots 170 and 163, these chucks are also angularly adjusted and will change the angle of the face 130 of the brush back with respect to the drill-

ing and tuft setting mechanism. It is, however, necessary to impart a further movement to the chuck in order that the face of the brush back in the various positions of registration and angular adjustment thereof will be in the same spaced relation to the drilling mechanism or the tuft setting mechanism. This is accomplished by the patterns 176 and 177 in conjunction with the thrust bars 174 and the thrust bearing 178. By properly fashioning these patterns each adjustment of the chuck vertically, horizontally and angularly will accomplish a corresponding adjustment of the frame 168 forwardly or rearwardly so as to maintain the proper relation of the brush back to the operating mechanism. The spring-pressed plungers 173 will always hold the frames 168 in contact with the patterns and thrust bearing.

20 To compensate for the deflection of the drill, when boring angularly, the amplitude of movement of the chuck for the tuft setting mechanism should be less than that for the drilling mechanism. This is accomplished by merely slightly adjusting the thrust bearing 178, which, by enlarging or diminishing the radial distances from the pivots 170 and 163 will correspondingly alter the length of movement.

30 The cams 22 and 23, which respectively control the slides 156 and 157, may be conveniently formed by manually setting the holders to successive positions of registration, according to the particular pattern desired and for marking the cam blanks in each of such adjustment positions. To facilitate this operation I have provided at the upper ends of the slides 156 and 157 threaded sockets for engaging threaded shanks 188 which pass upward above the top of the guide 155 and engage wing nuts 189, as shown by dotted lines in Fig. 7. By screwing these nuts upward or downward on the shanks the slides 156 and 157 will be raised or lowered, which will correspondingly adjust the positions of the chucks. Cam blanks may be marked by removing the rollers 158 and 159 and substituting a drill or other marking device for operating upon the cam blank. The blank thus marked can then be removed and cut to proper form, which will subsequently reproduce the original movement.

Complete assembly.

55 From the description of the several units constituting the complete machine, it will be observed that each of these units is practically a separate assembly, which is easily detached from the main machine and can be adjusted or replaced without affecting other parts of the machine. Thus the tuft picking mechanism constitutes a distinct assembly and the only connection between the mechanism thereof and that of the main machine is 60 through the link 51 which couples the bell crank lever 50 with the pitman 52. Therefore, this unit can be easily detached without disturbing other parts of the machine. The only connection between the bristle feeding mechanism and the other mechanism is 70 through the link 75 which actuates the reciprocatory member 44 and the pin 89 which connects the pitman 52 with the slide 88. The tuft setting mechanism constitutes another independent unit, which may be completely 75 assembled by itself and then mounted upon the machine, its only attachment to the other mechanism being through the pins 89 and 105, which are respectively connected with the pitmen 106 and 52. The housing or guide-way 100 of this unit is secured to the frame by bolts or screws 190, so that it may be quickly detached or exchanged for another similar unit. This is quite important, inasmuch as it is necessary to change the size 80 of the staple for different sizes of tufts and while the tuft picking mechanism may be adjusted for a large variation in sizes of tufts, the tuft setting mechanism must be exchanged. With my construction this exchange is easily and quickly accomplished 85 and without disturbance of the adjustment of other parts of the machine.

90 The drilling mechanism is a unit whose only connection to the other mechanism is 95 through the cam 24 and the work holding unit is also distinct from the other units of the machine.

95 In the complete operation the bristle holder is first adjusted to receive bristles of the desired length by sliding the plates 30 and 31 upon the shafts 26 and 27. The hinged cover 40 is then raised and the bristles inserted in the receptacle, the plunger 34 being first retracted and locked temporarily by the latch 39. The size of the tuft is adjusted by adjusting the screw-threaded stops 56 and 57 and also by adjusting the eccentric 83 to raise or lower the pin 82 on which the member 44 slides. The cams 23 and 24 having been 100 properly formed by the method above described, or by any other method, and all other necessary adjustments having been made, the machine is ready for operation. Motion is imparted to the shaft 2 from the pulley 3 105 driven by the belt 5 whenever the motor 4 is started. There is also a brake for instantaneously stopping motion at the completion of the cycle and this is preferably in direct engagement with the pulley 3. Thus, as shown, 110 said pulley is provided with a peripheral V-shaped groove 191 which is engaged by a corresponding V-shaped brake shoe 192 yieldably pressed into engagement by the spring 193. 194 is a solenoid, the core 195 of which 115 is connected by the links 196 with a cam 197 for retracting the brake shoe. This solenoid is included in the motor circuit 198, so that whenever the motor is started, the brake will 120 be released and, on the other hand, when the 125

motor is stopped, the brake will be instantaneously applied. The motor circuit is automatically opened at the completion of the large cycle or the completion of the filling of 5 all of the holes in the brush back, this being accomplished by a trip 199 on one of the cams 23 and 24, which actuates a cut-out switch 200.

When the motor is started, the shaft 2 is 10 revolved and with each revolution will complete a small cycle, which accomplishes the following operations. The bristles are fed downward in the bristle holder and are compacted to uniform density in the wedge-shaped space adjacent to the picking needles. The picking needles are operated to separate a tuft of predetermined size and to carry the same downward between the guides 59 and 60 into the slot 124 of the nozzle. The wire 15 is fed to the staple forming mechanism, is sheared to the proper length and is formed into a staple and this staple is then engaged with the tuft and with the latter is carried through the nozzle. The work holders have 20 simultaneously registered corresponding points on two brush backs with the drilling mechanism and the tuft setting mechanism and the drilling mechanism is operated to drill a hole in one back simultaneously with the insertion of the tuft and staple into the 25 corresponding hole in the other brush back. By reason of the angular advance of the crank pin 9 with respect to the crank pin 7, the nozzle will complete its forward movement 30 and will start upon its return movement in advance of the completion of the forward movement of the inserter. This results in holding the nozzle in contact with the brush back during the instant of transfer of the 35 tuft from the nozzle to the hole, but will retract the nozzle from such contact before the final driving blow on the staple is given. This avoids injury to the tuft, which might otherwise occur if the nozzle were in close 40 proximity to the back at such time.

What I claim as my invention is:

1. In a brush machine, a tuft picking unit including a pair of cooperating reciprocable tuft gathering members, a tuft setting unit 50 including a reciprocable nozzle operable transversely to said tuft gathering members, said tuft gathering members being arranged to directly deposit the tufts in said toggle, a frame on which said units are mounted, 55 each of said units constituting a complete assembly capable of independently performing its particular function and a common driving mechanism for operating said units with a substantially harmonic motion in timed 60 relation to each other.
2. In a brush machine, the combination of a bristle feeding unit, a tuft picking unit 65 cooperating therewith to successively pick and deliver tufts, adjustment means for varying the size of the tufts, a removable tuft set-

ting unit adapted to operate on a tuft of pre-determined size, and a common actuating mechanism for said bristle feeding, tuft picking and tuft setting units, permitting of the exchange of said tuft setting unit without 70 disassembling of the other units.

3. In a brush machine, the combination of tuft forming means, tuft setting means arranged to cooperate with said tuft forming means and including a nozzle, staple forming means and an inserter, and mechanism for operating said means in timed relation, 75 said tuft setting means being detachable from said machine as a unit without interference with or disassembly of said tuft forming means.

4. In a brush machine, the combination with tuft setting means and tuft picking and delivery means, of mechanism for operating said parts by timed substantially harmonic 85 movements comprising a rotating crank, a pitman connection between said crank and tuft setting means, and a bell crank connection between said pitman and said tuft picking and delivering mechanism. 90

5. In a brush machine, the combination with tuft setting mechanism reciprocating in one plane and cooperating tuft picking and delivering mechanism reciprocating in a transverse plane, of means for imparting to 95 said mechanisms properly timed substantially harmonic movements comprising a rotating crank, a pitman connection between said crank and said tuft setting mechanism, and a bell crank connection between said pitman and tuft picking and delivering mechanism. 100

6. In a brush machine, the combination with tuft setting mechanism including a reciprocating nozzle and a differentially reciprocating driver, of tuft picking and transferring means reciprocating in a plane transverse to the plane of movement of said nozzle and driver, and mechanism for imparting to said parts properly timed substantially harmonic cooperating movements comprising 110 a pair of cranks of different throw, pitman rods connecting said cranks respectively with said nozzle and driver, and a bell crank connection between the pitman for said driver and said tuft picking and transferring means. 115

7. In a brush machine, the combination of a tuft setting unit including a reciprocable nozzle having a tuft receiving opening therein, a reciprocable tuft transferring unit 120 arranged to directly deposit a tuft in said opening, and mechanism for imparting to each of said units a substantially harmonic movement in timed relation to the other, such that each of said units is in a low velocity 125 portion of its harmonic cycle during the interval when the tuft is deposited by said tuft transferring unit into said tuft setting unit.

8. In a brush machine, the combination 130

- with a reciprocable nozzle having a longitudinal passageway therethrough, and a transverse passageway intersecting therewith, of an inserter movable through said longitudinal 5 passageway, a reciprocable tuft picking and transferring unit arranged to directly deposit a tuft in the transverse passageway of said nozzle, mechanism for imparting substantially harmonic movements of different amplitude and angular displacement to said nozzle and inserter, and means for imparting a substantially harmonic movement to said tuft picking unit in timed relation to said tuft setting unit.
- 15 9. In a brush machine, the combination with a tuft setting nozzle unit having a transverse tuft receiving slot therein, of a reciprocable tuft picking and transferring unit arranged to directly deposit a bristle tuft in 20 said slot, a bristle feeding unit adjacent said tuft picking unit, said units being operable by substantially harmonic actuating movements, and a rotating shaft having eccentric connections with said units for imparting the 25 harmonic movements thereto in properly timed relation.
10. In a brush machine, the combination of a reciprocable tuft picking unit, a tuft set-
- ting unit including relatively movable nozzle and plunger members, said units being operable by substantially harmonic movements, and a common rotary drive member having a pair of eccentric connections for imparting said harmonic movements, one of said eccentric connections being connected to said nozzle member, the other being connected to said plunger member, and one of said pair of connections being also connected to said reciprocable tuft picking unit, said eccentric connections being angularly offset with respect to each other and of different amplitude.
11. In a brush machine the combination with reciprocable tuft setting means and reciprocable tuft picking and delivery means, of mechanism for operating said means by 45 timed substantially harmonic movements comprising a rotating crank, a pitman connection between said crank and said tuft setting means, and means connecting said tuft setting means with said tuft picking and 50 delivery means for transmitting the harmonic movement of the former to the latter in timed relation.

In testimony whereof I affix my signature.

CONRAD JOBST.
